ELECTRON DISCHARGE DEVICE FOR
ULTRA HIGH FREQUENCIES

Paul Georges Chevigny and Emile Labin, New York, N. Y., assignors to Federal Telephone and Radio Corporation, a corporation of Delaware

Original application February 16, 1942, Serial No. 431,134. Divided and this application December 6, 1943, Serial No. 513,000

8 Claims. (Cl. 315—5)

1

This invention relates to improvements in electron discharge devices and more particularly to such devices which embody integrally-formed cavity resonators for operation at ultra-high frequencies. The instant application is a division of our copending application, S. N. 431,134, filed February 16, 1942, now U. S. Patent No. 2,402,601 issued June 25, 1946.

An object of this invention is to provide an electron discharge device capable of high power output at ultra-high frequencies.

Another object of this invention is to provide an efficient and compact electron discharge device capable of operating at ultra-high frequencies with high applied voltages.

Still another object of this invention is to provide a novel form of adjustable cavity resonator.

An additional object of this invention is to provide a cavity resonator-electron discharge device combination in which a portion of the cavity resonator extends within the envelope of the electron discharge device with capacity coupling to the anode, while that portion of the cavity resonator outside of the envelope is tunable.

Generally speaking, this invention may be defined as comprising the constructions and combinations recited in the annexed claims and illustrated in certain embodiments in the drawings accompanying and forming a part of this application, wherein:

Fig. 1 shows a longitudinal section of a device embodying a preferred form of this invention;

Fig. 2 illustrates a partial longitudinal section of a device having an adjustable cavity resonator which can be used in place of the cavity resonator shown in Fig. 1;

Fig. 3 is a cross-sectional view taken along the line 3—3 of Fig. 2;

Fig. 4 is a longitudinal sectional view of part of a device having a different form of adjustable cavity resonator which can be used in place of that shown in Fig. 1.

The construction shown in Fig. 1 comprises a centrally located filament 10, constituting the cathode, connected in a usual manner with a filament midpoint lead 11 and filament terminal leads 12 and 13 which are brought out of the tube through the end of the insulating tube wall 14, composed of a vitreous substance through which the leads are sealed. The grid 15 is of the cylindrical type which may be formed in a well-known manner and placed concentrically around the filament. The anode 18 is of a cylindrical construction concentrically surrounding the grid and filament and is closed at its outer end 19. A cylinder 20 may act as a guide for cooling air to the anode 18 which also may be provided with fins (not shown). The wall of the insulating tube may be sealed to the circumference of the cylinder 20 by means of the annular seal member 21. A

2

cavity resonator 70 is generally toroidal in shape and passes through the glass envelope 14 at seals 71 and 72. One wall of the cavity resonator is connected to the control grid 15 and serves to support the same. The other wall of the cavity resonator is bent into a cylinder 73 closely surrounding the cylindrical anode 18 to form a capacity coupling between the cylinder and the anode. In the formation of the cavity resonator, care is taken to avoid sharp corners which would tend to introduce undesired resistance. For example, the corners 74, 75, 76 and 77 are well rounded.

Fig. 2 shows a tube provided with a cavity resonator which is adjustable for tuning purposes and which can be used in place of the cavity resonator shown in Fig. 1. The side walls 70a and 70b of the cavity resonator outside of the evacuated envelope are provided with identical spiral threads 78a, 78b and there is provided between the corresponding threads of these walls a spiral spring member 79, the ends of which overlap. One of the ends is rounded and bulged between the threads at 80, to make spring contact with the other end portion. Thus, by moving the member 79 around the spiral, its diameter may be correspondingly increased or decreased to change the size of the cavity resonator (see Fig. 3).

An alternative arrangement for varying the size of the cavity resonator is shown in Fig. 4, wherein structural elements of Fig. 1 are like-numbered. One of the cavity resonator walls is provided with an annular break at 82, on one side of which there is attached, as by brazing, an annular ring 83 which is threaded to receive the threads 84 of a cylindrical member 85. To prevent the occurrence of sharp corners within the cavity resonator, which is undesirable from an electrical standpoint, there may be attached, as by brazing to the inside of the cavity resonator wall, annular spring members 86 and 87 which make a wiping contact with the outer and inner peripheries respectively of cylinder 85. By this arrangement, the size of the cavity resonator can be varied by turning the cylindrical member 85 to increase or decrease its protrusion. It will be understood that in any of the embodiments, the part of the cavity resonator outside of the envelope may be made as a separate part and attached to the part protruding through the envelope, as by brazing, and need not necessarily be the same unitary sheet of metal as the part inside of the envelope.

The insertion of the coupling capacity between the cavity resonator and tube electrode is desired in order to allow different D. C. voltages to be applied to the electrodes. The use of the anode itself as one of the plates of the coupling capacity between the anode and cavity resonator, as used in the embodiments herein, constitutes a very effective means for obtaining the capacity

coupling, as the anode offers a relatively large surface close to the tube wall near which the tank member can easily be brought. The location of the plates of the coupling condenser within the evacuated vessel has the further advantage that the condenser plates can be brought closer together without the occurrence of sparking between them than would be possible in the atmosphere; and this enables the coupling capacity to be made larger with a consequent desired decrease in the voltage drop across it.

The constructions according to this invention in which the cavity resonator is brought through the glass to the outside of the vessel, while the coupling capacity is placed inside the vessel, is of special advantage, as the portion outside the vessel can be tuned by adjusting the size of the cavity resonator; and at the same time the effectiveness of the coupling capacity within the vessel is retained. The use of the coupling capacity between the cavity resonator and the anode is of special advantage because it enables the high D. C. voltage ordinarily placed on the anode to be kept off the resonator. This greatly simplifies problems of insulation, and results in enabling small cavity resonators to be used, which is a requirement for high frequency operation. By keeping the high D. C. anode voltage off the cavity resonator, the cavity resonator can be placed nearer the cathode, that is with a shorter section of glass between the cathode and cavity resonator than otherwise, and as the high D. C. voltage is between the anode and cavity resonator wall, the required insulation there-between can be provided by a sufficiently long section of the glass envelope wall between the cavity resonator and anode. This keeps the large D. C. voltage stress away from the glass section between the two walls of the cavity resonator which protrude through the glass, so that the only voltage across the glass extending between the walls is the oscillating or signal voltage between the anode and grid. This enables the two walls of the cavity resonator to be brought quite close together which correspondingly permits the use of a small cavity resonator, tunable to high frequencies.

The tube may be used in any well-known manner, for example, as an amplifier or an oscillator. As is well-known, to make the tube oscillate, it is only necessary to proportion the elements so that a sufficient feedback of energy from the anode circuit to the grid-cathode circuit shall occur to sustain the oscillations. Energy output may be taken from the devices in a convenient, practical manner. For example, a loop (not shown), may be placed in the cavity.

Accordingly, while we have described above the principles of our invention in connection with specific apparatus and particular modifications thereof, it is to be clearly understood that this description is made only by way of example and not as a limitation on the scope of our invention as set forth in the objects and the accompanying claims.

We claim:

1. An electron discharge device including a generally cylindrical, hollow anode, a generally cylindrical hollow grid structure positioned coaxially within said anode, a cathode positioned within said grid structure, a generally toroidal cavity resonator, a hollow cylindrical extension of one side of said resonator spaced from and surrounding said anode, a hollow cylindrical ex-

tension of the other side of said resonator supporting said grid structure, and envelope means surrounding said electrodes and supporting said cavity resonator.

5. An electron discharge device according to claim 1, in which a portion of said resonator extends through and is positioned outside of said envelope means.

3. An electron discharge device according to claim 1, in which said hollow anode is closed at one end and further comprises a hollow cylinder attached at one end about the closed end thereof, and projecting outwardly through said envelope means.

4. An electron discharge device according to claim 1, in which the inside of each side of said resonator is spirally threaded, and in which the periphery of the toroidal resonator consists of a spiral-shaped spring member extending between the threads of the two sides, the ends of the spring member overlapping one another.

5. An electron discharge device according to claim 1, in which one side of the resonator is provided with an annular opening and further comprises a hollow cylindrical member having one end extending through said opening, and means coupled to said cylindrical member for controllably adjusting the position of said cylindrical member within said opening.

6. An adjustable cavity resonator adapted for connection to vacuum tube electrodes comprising a pair of side walls, each of said walls being provided with a corresponding spiral thread, and a spiral-shaped spring member extending between the threads of the two walls, the ends of said spring member overlapping each other.

7. A cavity resonator according to claim 6, in which one end of said spring member is provided with a protuberance engaging the overlapping end of said spring member.

8. A tunable cavity resonator adapted for connection to vacuum tube electrodes comprising a pair of side walls, one of said walls having an annular opening, a cylindrical member adapted to enter said opening, a pair of annular curved spring members attached within said one of said resonator side walls, one of said spring members bearing along the outer surface of said cylindrical member and the other bearing along the inner surface of said cylindrical member whereby curved surfaces are provided from the cylindrical member to the wall through which it protrudes, and means coupled to said cylindrical member for varying the degree of entrance of said member.
